UNITED STATES PATENT OFFICE

102,949

DESIGN FOR A FONT OF HEBREW TYPE

Samu-El Ish-Shalom, New York, N. Y., assignor
to Mergenthaler Linotype Company, Brooklyn,
N. Y., a corporation of New York

Application July 16, 1936, Serial No. 63,876

Term of patent 14 years

To all whom it may concern:

Be it known that I, Samu-El Ish-Shalom, a citizen of the United States, residing in the city of New York, in the State of New York, have invented a new, original, and ornamental Design for a Font of Hebrew Type, of which the following is a specification, reference being had to the accompanying drawing, forming a part thereof. The figure of the drawing is a face view of the Hebrew type showing my design.

The new ornamental font of Hebrew type is characterized by the formation of the various letters, having horizontal and vertical strokes of the same thickness placed at an angle in relation to each other and with the letters uniformly proportioned.

I claim:

The ornamental design for a font of Hebrew type substantially as shown and described.

SAMU-EL ISH-SHALOM.
